(57) **CLAIM**

The ornamental design for a crate, substantially as shown and described.

DESCRIPTION

FIG. 1 is a front, left side and top perspective view of a crate comprising a new, original and ornamental design;
FIG. 2 is a bottom, front side and right side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the figures illustrate portions of the crate that form no part of the claimed design.

1 Claim, 8 Drawing Sheets
